United States Patent Office.

C. M. HAWES, OF NEW YORK, N. Y.

Letters Patent No. 80,732, dated August 4, 1868.

IMPROVEMENT IN PATTERNS FOR TRIMMING HAT-BRIMS.

The Schedule referred to in these Letters Patent and making part of the same.

TO ALL WHOM IT MAY CONCERN:

Be it known that I, C. M. HAWES, of the city, county, and State of New York, have invented a new and useful Improvement in Patterns for Trimming Hat-Brim; and I do hereby declare that the following is a full, clear, and exact description thereof, which will enable those skilled in the art to make and use the same, reference being had to the accompanying drawings, forming part of this specification.

This invention relates to a new and useful improvement in patterns for trimming hat-brims, and it consists in attaching the pattern to a revolving frame, constructed and arranged in such a manner as to admit of one pattern being readily detached from the frame, and another, of a different size, readily applied to it, so that hat-brims of different sizes may be trimmed, the revolving frame admitting of the work being done very expeditiously and in a perfect manner.

Hitherto the patterns have not been arranged so as to admit of the brims being trimmed with facility. Sometimes the pattern is simply held in one hand and turned by the operator in a very inconvenient way, while the knife is applied to the brim with the other hand; and some place the pattern on a rude stand or block on a bench or table, and turn the block while trimming the brim.

My invention, as will be presently seen, is a great improvement over either of these plans.

In the accompanying sheet of drawings—

Figure 1 is a vertical central section of my invention, taken in the line *z z*, fig. 2.

Figure 2, a plan or top view of the same.

Similar letters of reference indicate corresponding parts.

A represents a base, which may be constructed of wood or metal, and is provided with an upright central pin, *B*, and

C is a circular plate or disk, which is provided or formed with a central upright tube, *D*, through the top of which a screw, *E*, passes, and rests on the upper end of the pin *B* of base *A*, as shown clearly in fig. 1. By turning this screw, *E*, the plate *C* may be adjusted higher or lower, as desired.

To the plate *C* there are attached three upright springs, *F*, each of which has a pin, *a*, projecting at right angles from its upper end, and these pins fit in holes in the pattern *G*, and hold the latter firmly in position, the elasticity of the springs keeping the pins in the holes in the pattern.

It will be seen from the above description that the pattern *G* may be readily turned or rotated, and the brim of the hat, when the hat is placed on the pattern *G*, trimmed with the greatest facility by applying a knife to the edge of the brim, the edge of the pattern serving as a guide.

In order to detach one pattern, *G*, and apply another, all that is required is simply to compress the springs *F*, so as to draw their pins *a* out from the holes in the pattern, and then fit the other pattern over the springs, so that the pins may pass into its holes.

I claim as new, and desire to secure by Letters Patent—

The revolving plate *C*, with upright springs or elastic bars *F* attached, provided with pins *a*, at their upper ends, to fit in holes in the pattern *G*, all arranged substantially in the manner as and for the purpose set forth.

C. M. HAWES.
